(57) **CLAIM**

The ornamental design for a display module, as shown and described.

DESCRIPTION

FIG. 1 is a perspective view of the display module according to an embodiment that includes a cover window and a display panel attached to the rear side of the cover window and is used for electronic devices, such as smartphones, mobile phones, portable communications devices, multimedia devices, etc.

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

Referring to FIG. 8, the shaded area corresponds to a screen that is used as a display screen for electronic devices to display videos, images, text, icons, information, etc.; however, the shading is shown for reference only and forms no part of the claimed design; and,

Referring to FIG. 9, the cover window has a protruding part in the top center, and a sensor, a camera, a speaker, etc. may be positioned corresponding to the protruding part to increase the screen size while implementing a substantially rectangular screen.

The broken lines shown in the drawings are included for the purpose of illustration and form no part of the claimed design.

1 Claim, 9 Drawing Sheets
